UNITED STATES PATENT OFFICE.

LAWRENCE C. TURNOCK, OF EDGEWOOD, PENNSYLVANIA.

METHOD AND APPARATUS FOR ELECTRODEPOSITION.

Application filed December 17, 1925. Serial No. 75,957.

The present invention relates broadly to the art of electrodeposition, and more particularly to the art as applicable to the use of precious metals such as gold and silver. Furthermore, the invention has particular utility as applied to the art of electroplating comparatively large objects, such as band and orchestra instruments and the like, which have a relatively large surface area as compared with small articles of jewelry and objects of similar nature. The word "band" will hereinafter be used generically as definitive both of band and orchestra instruments, the distinction between such instruments quite frequently being in the manner of their ultimate use and not in any features of construction.

When plating articles such as band instruments and the like, and especially with the metals gold and silver, the problem of obtaining and insuring accuracy in the weight and thickness of the deposit of metal is of extreme importance owing to the monetary value represented in the deposited metals. Not only is it desirable to deposit on such articles the minimum weight and thickness of metal coating consistent with obtaining a plated article that will be guaranteed a serviceable life of reasonable length before the metal coating becomes impaired, but it is likewise particularly desirable and important that there be uniformity in the weight and thickness of metal deposited per unit of exposed surface area on all such articles irrespective of their total surface area.

Until comparatively recently, the only method of controlling or ascertaining the amount of metal deposited in a plating bath has been to utilize an ammeter and estimate the average current flow during the given period of plating. The product of the estimated average current in amperes and the elapsed time in hours gives the approximate number of amperehours of electricity passed, and enables the weight of the deposit of metal to be roughly calculated.

In my prior United States Patent No. 1,527,095, granted February 17, 1925, there are disclosed certain improvements in the art of electroplating and more particularly with respect to a method of obtaining great accuracy with respect to the coating on each individual article. The present invention is adaptable in accordance with the disclosure

of said patent for the individual control of deposited metal on a single article, or for the control simultaneously of a plurality of articles in a common bath or in a number of baths.

When gold is the metal being deposited, special problems have heretofore presented themselves due to the fact that the plating operation has usually comprised, in reality, a flashing of the metal onto the articles. The current flow as well as the duration of the plating period in such cases are both so small that difficulty has been encountered in attempting to actually measure the equivalent quantity of electricity passed, from which the weight of metal deposited is in turn calculated. With some of the smaller articles, such as jewelry and the like, it has heretofore been proposed to utilize meters, but due to the difficulty referred to, where meters have actually been used with gold plating, it has been customary to provide two meters connected in series for each bath. One of these meters has recorded both the auxiliary load and the quantity of electricity passing to the plating bath, while the other has recorded only the auxiliary load. The difference in reading between the meters has then been used to determine the amperehours of electricity passed, and from this value the amount of metal deposited. This operation, however, is not entirely satisfactory as it involves the possibility of error both in meter readings and comparisons, as well as the possibility of a difference in accuracy as between the meters.

In view of these objections and difficulties with the plating of smaller articles with precious metal, it is common practice with comparatively large articles, and for example, in all band instrument establishments throughout the world, to make only crude approximations, no meters integrating time and current factors having ever been used to my knowledge in this connection for either gold, silver or other metals prior to my own commercial adaptation of such meters. As the surface areas of articles such as band instruments are necessarily comparatively large, it will be apparent that any error of calculation or approximation resulting in an extra heavy deposition being received by the articles is necessarily expensive, and particularly so when plating with gold from a cy-

anide bath from which the rate of deposit of gold at the same current flow is substantially three times as rapid as when plated with gold from a gold chloride bath. In order, however, to maintain and insure a given standard of excellence of metal coating, it is obvious that any error, where approximation is the basis of operations, must be on the side of too heavy a deposit.

10 The present invention has for one of its objects to provide an improved method of plating comparatively large articles, and particularly band instruments and the like, with gold or silver.

15 Another object of the invention is to provide an improved meter adapted for use with gold cyanide baths, and particularly such baths as adapted for the application of protective or ornamental metal coatings to articles of the character referred to, or to other large articles of the general nature herein-after referred to.

Still another object of the invention is to provide means of keeping an exact record 25 of all metal going onto the plated articles. Heretofore, the manufacturers of band instruments for example, have been obliged to ascertain the amount of metal, and especially gold or silver, plated on their product by 30 noting the loss in weight of their anodes from one day to the next. This method not only involves considerable error, but requires the removal of the anodes from the tanks, together with the loss of considerable time.

35 In the drawings, there are shown for purposes of illustration only, certain preferred embodiments of the present invention, it being understood that the drawings do not define the limits of my invention, as changes in 40 the construction and operation disclosed therein may be made without departing either from the spirit of the invention or the scope of my broader claims.

In the drawings:

45 Figure 1 is a diagrammatic view illustrating a plating bath and the circuit connections therefor;

Figure 2 is a front elevational view, largely diagrammatic, illustrating a meter constructed in accordance with the present invention and having its dial reading directly in units of gold deposited from a cyanide bath; and

50 Figure 3 is a view similar to Figure 2 illustrating a meter having its dial calibrated to read directly in units of silver.

I have found that when working with gold cyanide baths the theoretical amount of gold deposited per amperehour on the article being plated is 4.728 dwt. Working on this basis I have had meters constructed in which the dials read directly in unit weights of metal deposited, the desired readings being obtained by construction, subdividing and 55 marking the dials on the basis that each am-

perehour of electricity passing through the bath is equivalent to approximately 4.728 pennyweights of gold. It will be understood that the value or constant 4.728 is based on a theoretical plating efficiency of 100%, this 70 constant varying as the percentage of efficiency varies. It will be understood, however, that the present invention contemplates the use of this constant, or certain multiples thereof on the basis of the efficiency referred 75 to, together with any changes that may be required by reason of this efficiency or character of the bath.

In Figure 2 of the drawings there is illustrated a meter M having a dial 2 with graduations 3 reading directly in pennyweights of gold in accordance with the present invention. It will be obvious that on the basis of the constant 4.728, other readings directly in grains or grams may be readily calculated. 80 Such a dial enables the meter to be read directly in weights of gold and a predetermined weight having been calculated for a given article or series of articles, a glance at the meter will instantly show when the desired 85 amount of metal has been deposited. The use of such a meter makes it possible to obtain great accuracy in the desired weights of deposited metal as well as great accuracy in the uniformity of plate on different articles such 90 as band instruments or the like, thereby insuring the manufacturer against any great loss of metal by reason of deposits which are too heavy. Furthermore, the use of such a 95 meter makes possible the adoption of standards of weight and thickness of gold or silver or other metal plate to different size instruments or similar articles, and likewise greatly facilitates the execution of such established standards. Heretofore similar articles have 100 shown a lack of uniformity due to the absence of an effective means of executing any given standards, accurate control having been extremely difficult with respect to time and current factors in view of the personal equation 105 and judgment of the operators.

Where silver is the metal being deposited, the constant is 2.588 dwt. of metal per amperehour, and the meters in such cases are similarly graduated to read directly in unit 110 weights of silver. Such a meter is indicated at M' in Figure 3 in which the dial 2' has graduations 3' reading directly in pennyweights of silver, such meter being adapted for the silver plating of large objects of the 115 character herein set forth.

The present invention also enables the weight and accordingly the thickness of the plating to be automatically controlled and the plating period definitely terminated without the intervention of the operator. In Figure 1 of the drawings there is illustrated more or less diagrammatically one form of circuit involving the present invention. In this figure there is indicated a source of direct cur- 120 125 130

rent G having its positive terminal connected to a line L. This line may have any desired number of branches such as indicated at 4 and 5 each of which may lead to one or more 5 anodes A in a plating tank or tanks T. The cathode or cathodes C in each of these tanks are in turn connected to one side of a meter M of the character illustrated for example in Figure 2 of the drawings. By reason of the 10 location of the meter on the cathode side of the circuit, they are only effective for measuring the actual flow of electricity which has been effective on the cathodes. I have found such a positioning of the meter to be highly 15 desirable as compared with the positioning on the anode side of the circuit, inasmuch as the total flow through the anodes may not be effective for plating purposes due to leakage or other losses. The opposite side of each 20 of the meters is connected to a common wire 6 leading to one terminal of a totalizing meter TM, the connection of each meter to the common wire 6 preferably including a circuit breaker 7 for the purposes hereinafter referred to. The opposite side of the totalizing 25 meter is in turn connected to the negative terminal of the source of current.

Each of the meters may have a pointer 8 adapted to cooperate with the calibrations 3 and a hand 9 adapted to be manually moved to any desired position. Having determined the desired amount of metal to be deposited, the hand 9 of each of the meters 3 will be set at the desired point. Upon establishing a 35 flow of electricity, the pointer 8 of each of the meters will commence its travel in a clockwise direction in accordance with the actual flow of electricity. The hand 9 of each of the meters M has a connection 10 to one side of an auxiliary line w, while the pointer 8 of each meter has a similar connection 11 to the opposite side of an auxiliary line w', this last mentioned connection including a magnetic coil 12 cooperating with the circuit breaker 7. By reason of this construction, when the 45 pointer 8 coincides with the position of the hand 9, the circuit will be closed through the coil 12 thereby operating the circuit breaker to open the circuit to the particular bath controlled by that meter. It will thus be seen that the plating operation can be automatically terminated at will.

The totalizing meter TM may be of any desired construction adapted to read directly in unit weights of metal, whereby it is possible to determine the actual amount of metal deposited by merely glancing at the totalizing meter. This obviates the necessity of bodily removing the anodes from the bath 50 and weighing the same as has heretofore been necessary.

So far as I am aware, it has heretofore never been proposed to utilize a meter integrating the current and time factors on an 65 electroplating bath for comparatively large

objects as herein contemplated, and it has never been proposed to calibrate a meter dial for gold cyanide baths to read directly in units of metal deposited. Had it heretofore been proposed to utilize meters for use in 70 plating large objects, it is likely that such practice would have followed the practice as applicable to smaller objects, and would have required the use of two meters for each bath as herein set forth. By my invention the use 75 of meters is not only extended to a new field, but the manner of utilizing the same is radically changed so as to require only a single meter in place of the plurality of meters heretofore required. 80

It will be apparent to those skilled in the art that the present invention is applicable to other large objects and to the plating of such objects with other metals. In this connection reference may be made to the adaptability of the invention to use with automobile radiator shells, bumpers, lamps and the like with protective or ornamental coatings of metals such as nickel, chromium, and cadmium, thereby affording the desired thickness 90 of deposit per unit area of the plated article.

Certain advantages of the invention arise from the utilization of meters in the art as applicable to comparatively large objects, 95 and more particularly to band instruments and the like, and especially meters having dials calibrated to read directly in unit weights of the metal deposited.

Other advantages of the invention arise 100 from the provision of means in a plating operation of the character herein contemplated whereby the actual amount of gold or other metal utilized during any period, or over any time interval, may be quickly and accurately 105 determined without the necessity of actually weighing the anodes.

Still other advantages of the invention arise from the provision of a meter for use with gold cyanide baths having its dial graduated to read directly in unit weights of gold. 110

Still further advantages arise from the method of determining dial readings for a meter as referred to by arranging the usual 115 graduations as used for amperehours on the basis of one amperehour being equivalent to substantially 4.728 of pennyweights of gold with a 100% plating efficiency.

I claim:

1. In an electro-plating system, the combination of an electro-plating bath, an anode and a cathode therein, a source of electromotive force connected to the anode, and a meter for indicating the amount of metal deposited at the cathode in accordance with the current traversing the cathode, of electrically operated means for interrupting the electrical circuit including the bath after a predetermined amount of metal has been deposited, the circuit interrupting means being so connected to 120 125 130

the meter that the indications of the meter are not influenced by the electrical currents actuating the interrupting means.

2. In an electro plating system, a plurality of plating baths each containing at least one comparatively large object to be plated and constituting a cathode, at least one anode in each bath, a circuit including said anodes, means effective while the anodes are in position in their respective baths for indicating the amount of metal deposited on the articles, and means controlled by the indicating means for separately interrupting the plating current of any bath when a predetermined amount of metal has been deposited therein.

3. In an electro plating system, a plurality of plating baths each containing an object to be plated and constituting a cathode, at least one anode in each bath, a circuit including said anodes, means effective while the anodes are in position in their respective baths for indicating the amount of metal deposited on said objects, and electrically controlled means for separately interrupting the plating current of any bath when a predetermined amount of metal has been deposited thereon.

In testimony whereof I have hereunto set my hand.

LAWRENCE C. TURNOCK.
